(57) **CLAIM**

We claim the ornamental design for a tissue fastening instrument, as shown and described.

DESCRIPTION

FIG. 1 is a bottom view of a tissue fastening instrument in an initial tissue capture orientation according to an embodiment of the invention.

FIG. 2 is a top view of the tissue fastening instrument depicted in FIG. 1.

FIG. 3 is a rear, end view of the tissue fastening instrument depicted in FIG. 1.

FIG. 4 is a front end view of the tissue fastening instrument depicted in FIG. 1.

FIG. 5 is a left side view of the tissue fastening instrument depicted in FIG. 1.

FIG. 6 is a right side view of the tissue fastening instrument depicted in FIG. 1.

FIG. 7 is a top, front perspective view of the tissue fastening instrument depicted in FIG. 1.

FIG. 8 is a top, rear perspective view of the tissue fastening instrument depicted in FIG. 1.

FIG. 9 is a top view of the tissue fastening instrument of FIG.

2 in an intermediate tissue capture orientation; and,

FIG. 10 is a top view of the tissue fastening instrument of FIG.

2 in a completed tissue capture orientation.

The broken lines shown in the figures represent portions of the tissue fastening instrument that form no part of the claimed invention.
